THOMAS B. ESTEP AND WILLIAM C. HEFFERMAN, OF CINCINNATI, OHIO.
ASSIGNORS TO THOMAS B. ESTEP.

Letters Patent No. 69,420, dated October 1, 1867.

IMPROVEMENT IN COFFINS.

The Schedule referred to in these Letters Patent and making part of the same.

TO ALL WHOM IT MAY CONCERN:

Be it known that we, THOMAS B. ESTEP and WILLIAM C. HEFFERMAN, of Cincinnati, Hamilton county, State of Ohio, have invented new and useful Improvements in Coffins; and do hereby declare the following to be a full, clear, and exact description thereof, reference being had to the accompanying drawings, making part of this specification.

Our invention consists in a cheap, simple, and secure device for hermetically closing the joint where a coffin-lid joins the body, thus preventing the escape of offensive and contagious odors from the corpse. In the accompanying drawings—

Figure 1 is a transverse vertical section of a coffin embodying our improvements, the lid being detached from the body.

Figure 2 is a similar section, with the lid attached to the body.

A represents the body of the coffin, and the upper edges of the side and end boards which constitute this body are provided with a number of convex corrugations, *a*, which extend completely around the coffin. The lid *B* has a groove, *b*, sunk in its under side, and said groove is adapted, when the lid is in position, to fit over the upper corrugated edges of the body. Secured to the under side of the lid, so that their front sides would be flush with the inner edges of the groove *b*, are cleats *C*, whose bottom portions have attached to them, by mouldings *D*, one edge of an India-rubber gasket, *E*, and the other edge of this gasket is secured between the moulding *F* and the bottom of the lid *B*. The rubber is drawn tight between these two mouldings, as shown in fig. 1, and both sides of the gasket which come in contact with any portion of the lid should be covered with white lead or other suitable cement. When the lid is screwed down on the body of the coffin, this gasket is pressed tightly against the top and inner sides of the body, and thus forms a perfectly air-tight joint, through which no gas or odor can escape.

This mode of rendering a coffin air-tight is very simple and effective, and will always be reliable, no matter how much the coffin sides should warp or spring.

We claim herein as new, and of our invention—

A coffin, whose upper edges of the body *A* are provided with corrugations *a*, when used in connection with grooved lid *B* *b*, cleat *C*, and India-rubber gasket *E*, the whole being arranged and operating substantially as herein described and set forth.

In testimony of which invention we hereunto set our hands.

THOMAS B. ESTEP,
WILLIAM C. HEFFERMAN.
